CLOTHES DRIER

Joseph Sekavec, Chicago, Ill.

Application September 1, 1932, Serial No. 631,362

8 Claims. (Cl. 100—50)

My invention relates to improved clothes driers for laundry purposes, preferably, though not necessarily, of a type which can be conveniently associated with domestic washing machines.

My object primarily is to provide a structure by which a compressive force is applied to a body or mass of clothes in a suitable vessel or receptacle with sufficient intensity to squeeze the water from the mass, and render the clothes dry to that extent that they are in condition for hanging to complete the drying in the usual way.

A further object is to provide a clothes drier structure which will have a clothes receptacle adequate for rinsing purposes and will have within said receptacle a compressing or squeezing mechanism capable of squeezing water from the clothes to the desired degree of dryness.

A further object is to provide a drier structure of this character having a vessel or receptacle for the clothes and having compressing or squeezing mechanism therein which is adaptable to different volumes or masses of clothes and which will just as effectively and uniformly remove the water from a relatively small load as from the maximum load within the capacity of the particular structure employed, my purpose being further to provide a novel and practicable means for readily adjusting the capacity of the structure to the particular volume of clothes to be treated.

A further object of my invention is to provide a simple and extremely practicable power mechanism for supplying the necessary compressive force to the squeezers within the vessel or receptacle, which power mechanism is preferably, though not necessarily, intended to be motor driven and which will not interfere with the use of the receptacle for rinsing purposes.

Other objects of my invention will appear hereinafter.

In the accompanying drawings, a drier structure is illustrated, which embodies the principles of my invention. In these drawings,

Fig. 1 is a vertical sectional view of the complete drier structure including the rinsing receptacle, squeezing mechanism and the power mechanism for the operation thereof;

Fig. 2 is a horizontal section on the line 2—2 of Fig. 1, illustrating the upper squeezer head or cover plate, and with portions broken away to reveal the lower squeezer member; and

Fig. 3 is a horizontal section on the line 3—3 of Fig. 2, illustrating the hydraulic pressure cylinders and the pumping mechanism for pumping fluid to the cylinders.

The structure in general includes a cylindrical

vessel or receptacle A, of sufficient diameter and depth to provide adequate capacity for rinsing purposes. This container is preferably supported by suitable legs 1 to position it at the proper height from the floor and can be provided with casters if desired, so that the machine is readily portable. Beneath the receptacle the hydraulic power mechanism B is positioned.

The receptacle is preferably made of suitable sheet metal and is closed at its lower end by a bottom wall 2 which merges with the vertical side wall 3. The upper end of the receptacle is open for access to the interior thereof. The upper marginal portion of the wall 3 is enlarged in diameter to form an annular shoulder 4 which merges with the side wall in a rounded edge 5 to assist in centering and guiding the removable cover or squeezer head when it is inserted into the receptacle. The lower portion of the side wall which merges with the bottom wall is preferably straight vertically and provides a well 6 in the bottom into which the water drains which is squeezed or compressed from the clothes. A drain cock 7 is provided at the bottom of the receptacle for the purpose of draining off the water therefrom.

Between the straight-sided lower portion of the vessel and the upper marginal portion thereof, the side wall is provided with a series of interior horizontal parallel shoulders or retainer members 10 extending throughout the entire circumference of the receptacle. If the vessel is made of sheet metal, these shoulders can be conveniently formed by corrugating the metal to form annular grooves 10a, but it is understood that they may be constructed in any other manner suitable for the purpose. The purpose of these shoulders is to provide retainer means at different levels or heights of the receptacle to which the cover member or upper squeezer head may be adjusted to vary the capacity of the drier in accordance with the desired quantity of clothes to be compressed.

The cover or upper squeezer member preferably comprises a flat circular disc or plate 12 of sufficiently less diameter than the inner diameter of the receptacle to provide clearance whereby it may be freely inserted in or removed from the receptacle or adjusted vertically therein. Around its margin this cover has an upstanding integral flange 13 which reinforces the plate. A suitable flexible gasket 14 surrounds the flange to seal the opening between the cover plate and the receptacle wall and prevent the escape of water when

the clothes are being subjected to compression by the squeezing mechanism.

The cover member is provided with several, preferably three, locking segments or latching members 15 on the upper side thereof for the purpose of locking the cover at any level or height to which it is adjusted. These locking segments are equally spaced around the margin of the cover and are adapted to be shifted radially to

10 project them beyond or withdraw them within the margin of the cover plate. When projected beyond the margin, they enter the groove 10a and engage the shoulder 10 and retain the cover plate stationary at its adjusted level.

15 The advantage of having shoulders 10 extending entirely around the vessel wall is that the cover need not be rotatably adjusted to any particular position but may be indiscriminately positioned with relation to the retaining shoulders. The segments are com-

20 paratively wide, so that collectively they occupy a considerable portion of the circumference of the shoulders and effectively distribute the strains imposed thereon by the pressure applied to the cover plate when the clothes are being com-

25 pressed. The outer edges 16 of these segments are preferably curved on the same radius as the shoulders so that they will conform to the curvature of the wall. These segmental latches or

30 keepers have radially disposed tongues 17 which slide in guides 18 suitably formed on the upper side of the cover plate. The segments rest upon the marginal flange 13 of the cover plate whereby the pressure on the cover plate is applied to the locking segments in close proximity to the marginal edges thereof, which effectively prevents bending or distortion of the locking seg-

35 ments.

The locking segments are actuated by means of a centrally disposed operating handle 18 which is carried by an upstanding post 19. The post has a reduced shank 20 journaled in a bearing formed in an upstanding boss 21 in the center of the cover plate and is held in place by a washer 22,

40 secured by a screw 23 to the lower end of the shank. A disc 24 is splined to the shank 20 above the boss 21 and is rotatable by the handle. The outer margin of the disc 24 bears upon an integral upstanding circular rib 25 formed on the upper side of the cover plate.

45 Links 26 are pivotally connected to this central disc 24 and to the tongues 17 of the locking segments, and operate in conjunction with the center disc to form toggles for shifting the locking segments radially when the handle is rotated.

50 It will thus be seen that when the segments are withdrawn, the cover plate can be conveniently inserted into or removed from the vessel or adjusted to any desired height or level. By simply rotating the operating handle and thereby projecting the locking segments beyond the periphery of the cover plate into engagement with the shoulders 10 of the receptacle wall, the cover plate can be firmly locked in place and the structure made capable of resisting the pressure when applied. The cover plate can be further reinforced by integral radial ribs 27 extending between the circular rib 25 and the marginal flange.

55 On account of the tremendous strain to which the receptacle wall is subjected when squeezing pressure is applied, the wall of the receptacle is reinforced by means of an outer casing 30 which surrounds the receptacle and which extends from the upper end thereof downwardly below the bottom thereof. This outer casing is preferably 60 formed to the contour of the outside of the ves-

sel structure and is preferably welded at various points to unite the receptacle and this casing in a rigid structure. The casing finishes off the outward appearance of the machine and the lower portion 31 thereof extends sufficiently below the bottom of the receptacle to provide means to which the supporting legs 1 are attached and to form an enclosure for the greater portion of the power mechanism.

65 The movable squeezer head or member 35 is 10 in the form of a disc or plate having a flat upper surface 36 and a depending integral marginal flange 37 for reinforcement. This member occupies a position in the lower portion of the receptacle and is preferably of sufficiently less diameter 15 than the inner diameter of the lower portion of the receptacle to provide clearance and permit the water to drain into the well. The lower pressure head, in a sense, forms a table in the receptacle upon which the clothes are placed. It is low 20 enough to not interfere with the use of the receptacle for rinsing purposes, the receptacle being simply filled with water to the desired level above the pressure member.

25 The pressure member, however, is movable toward and from the upper head or cover and is actuated by power mechanism to compress or squeeze the body of clothes between these two members. As the water is squeezed out of the clothes, it drains down into the well 6 around the 30 margin of the lower head and also through numerous holes or perforations 38 distributed throughout the area of the disc 35. From the well the water can be drained off through the drain cock 7.

35 In the present structure, I provide hydraulically operated means for actuating the movable squeezer head. This mechanism embodies a plurality of cylinders 40 in which movable plungers 41 are adapted to reciprocate. These cylinder 40 and plunger units are disposed vertically and there are preferably three of them arranged, as shown more clearly in Fig. 3, in equilateral triangular relation whereby power can be applied at three equally spaced points to the squeezer head. The squeezer head is supported upon the upper ends of the plungers through the medium of universal bearings 42 which permit the pressure head to adapt itself to varying thicknesses in the body of clothes compressed between the 50 two squeezer heads and enables the pressure to be effectively applied throughout the body of clothes. These bearings are in the form of balls and the upper ends of the plungers are cupped out to provide sockets therefor. The upper portions of the ball members are seated in inverted cup members 43 which bear against flat surfaced bosses 44 integrally formed on the under side of the squeezer disc 36. These cup members have flanges 45 and are held in place by the flanged 60 rings 46 which engage said flanges 45. The flanged clamping rings are secured to the bosses by the screws 47. While this construction provides very effective universal bearings between the squeezer head and the plungers for the purposes of transmitting the power of the plungers to the squeezer head, the squeezer head is not actually connected with these plungers, so that it can be detached by simply lifting it off its supports and removed from the receptacle if it is 65 necessary to gain access to the well below.

70 The main pressure cylinders 40 are shown at being formed integrally with the bottom wall 2 of the receptacle, although they may, for manufacturing reasons, be formed separately if de- 75

sired. The lower ends of the cylinder chambers are reduced in diameter to form shoulders 48 which serve as lower limit stops for the plungers and at the same time provide a fluid chamber below the plunger for insuring the entrance of operating fluid beneath the ends of the pistons.

Within the center of the triangle formed by a group of pistons, a reservoir 50 is positioned, which contains the supply of fluid, such as oil, which is pumped into the cylinders for actuating the plungers. This reservoir has lateral arms 51 radiating therefrom to the cylinders, and these arms have at their ends rings 52 which surround the lower ends of the cylinders. The rings are split diametrically on the line 53 whereby their outer portions 54 are detachable, and both portions of the rings are provided with outstanding lugs 55 through which clamping bolts 56 extend. The parts are so proportioned that the rings can be clamped tightly upon the cylinders and thereby support the reservoir and its associated parts firmly in proper position with relation to the cylinders.

The outstanding arms 51 are bored out cylindrically to form cylinders for small pump pistons 57 adapted to be reciprocated therein. These pistons have communicating longitudinal ports 58 (Fig. 3) and transverse ports 59, the ports 59 communicating with the supply of fluid in the reservoir to admit fluid to the pump cylinders ahead of the pistons. These ports 58 are controlled by ball check valves 60 which admit oil to the pump cylinders on the return stroke of the piston and which close on the forward stroke of the piston. In like manner, the outer ends of the pump cylinders communicate through ports 61 with the lower ends of the cylinders 49 which ports are likewise controlled by ball check valves 62 for admitting fluid to the cylinders 49 on the pressure stroke of the pistons and close on the ports upon the return stroke of the pistons.

The individual pistons 57 are actuated from a vertical shaft 63 within the reservoir, this shaft being provided with suitable bearings 64 in the upper and lower walls of said reservoir. The shaft carries an eccentric member 65 which is positioned in relation to the inner ends of the pump pistons whereby when the eccentric member is rotated by the shaft, it will impart outward or pumping strokes to the pistons. A loose ring 66 surrounds the periphery of the eccentric member and is interposed between said member and the ends of the pistons so that the eccentric member revolves within this ring, the purpose in this construction being to reduce the amount of relative movement between the ends of the pistons and the eccentric member to eliminate undue wear. Each of the pistons are yieldingly urged inwardly toward the eccentric member by springs 67 within the pump cylinders thereby providing for the return strokes of the pistons. At its lower end, the operating shaft 63 carries a pulley 68 for a driving belt 69 which can be driven from an electric motor or any other suitable source of power not shown.

It is thus seen that when the shaft is driven, it will operate the individual pumps and force fluid into the main cylinders for actuating the pressure plungers 41, thus forcing the squeezer head upwardly against the mass of clothes between the squeezer heads and forcing the water from the clothes. In the structure shown, I prefer to interconnect the main operating cylinders to equalize the pressure developed therein. For this purpose pipes 70 extend between each of the cylinders and

communicate therewith in the lower portions thereof through the ports 71. Cross-connecting the cylinders in this manner permits any one or two of the pumps to supply fluid under pressure to all of the cylinders in the event that one or more of the pumps become damaged or the valves fail to operate. It is desirable to have a pressure relief valve 72 of any suitable or standard type which can be set to operate at any desired predetermined pressure and which, when it responds to excess pressure, will by-pass the fluid to the reservoir. This valve is connected, as shown in Figs. 1 and 3, for convenience in one of the cross-connecting pipes 70 and its outlet port is connected by the by-pass 73 to the reservoir. In the event that the pressure in the system becomes greater than that for which the valve 72 is adjusted, the excess pressure operates said valve 72 and permits the pumped fluid to return through the by-pass 73 to the reservoir. A pipe 74, as shown in Fig. 1, extends from the bottom of one of the pressure cylinders 4 and communicates with the upper end of the reservoir through a suitable hand-operated valve 75 to return the fluid from the pressure cylinders to the reservoir when it is desired to release the pressure on the clothes and lower the squeezer head. This valve is normally closed during the operation of the pumps, but when opened it permits the oil to flow from all of the pressure cylinders through the cross-connecting pipe 70 and the return pipe 74 into the reservoir.

While I have herein shown and described a structure which is well adapted to carry out the principles of my invention, it is obvious that changes may be made in the construction, operation and arrangement of the parts, without departing from the spirit of the invention, and I contemplate such changes as fairly fall within the scope of the appended claims.

I claim:

1. In a clothes drier of the class described, the combination of a cylindrical receptacle, a movable squeezer head therein, means for actuating said movable squeezer head, and a stationary squeezer head adjustable relatively to the movable head to vary the compression space between said heads, and including a plate, locking means mounted on said plate, and means on the interior wall of the receptacle forming a plurality of annular channels at different levels, and adapted to be engaged at any point in the circumference of said channels by said locking means for holding the squeezer head in the position to which it is adjusted.

2. In a clothes drier of the class described, the combination of a receptacle for the clothes and a pair of squeezer members within said receptacle and between which the clothes are adapted to be compressed to force water therefrom, one of said squeezer members being stationary and the other being movable toward and from said stationary member, locking members on said stationary member, means on the stationary member for actuating said locking means, means on the interior wall of said receptacle forming annular channels disposed in parallel relation at different levels, said locking members on said stationary member being adapted to engage said channels at any point in the circumference thereof for positioning said stationary member relatively to the movable member for varying the compression space between said members, and power means for actuating said movable member.

3. In a clothes drier of the class described, the combination of a cylindrical receptacle having an

- open upper end and a plurality of annular interior shoulders around its wall at different levels, a cover member rotatable within the receptacle and adjustable to said different levels and having locking members for detachably engaging the shoulder at the level to which the cover is adjusted and in any rotated position of the cover, a bottom compressor plate in said receptacle spaced below the cover and between which and the cover the clothes are adapted to be positioned, and power mechanism for forcing the compressor plate toward the cover to compress the clothes therebetween.
4. In a structure of the class described, the combination of a cylindrical vessel having an open upper end and a closed bottom, a plurality of retaining members on its inner side wall arranged at different levels with respect to the height of the vessel and extending annularly around said wall, a removable cover plate adjustable in said vessel to different levels corresponding to said retaining devices and having at its margin locking members for cooperation with said retaining devices at any point in the circumference thereof, means carried by said cover plate for actuating said locking members to engage the retaining devices and in the level to which the cover plate is adjusted, a movable plate within the lower portion of the container and spaced below the cover plate, and means for actuating said movable plate to force it toward the positioned cover plate and compress the clothes within said space.
5. In a structure of the class described, the combination of a cylindrical vessel having an open upper end and a closed bottom, a plurality of retaining devices on its inner side wall arranged at different levels with respect to the height of the vessel and extending annularly around said wall, a removable cover plate adjustable in said vessel to different levels corresponding to said retaining devices and having at its margin radially movable locking members for cooperation with said retaining devices at any point in the circumference thereof, means carried by said cover plate for actuating said locking members to engage the retaining device at the level to which the cover plate is adjusted, a movable plate within the lower portion of the container and spaced below the cover plate and power means for actuating said movable plate.
6. In a structure of the class described, the combination of a cylindrical vessel open at its upper end and closed at its lower end, a plurality of annular shoulders formed in the side wall of said vessel and arranged in parallel spaced relation with respect to the height of the vessel, a plate in said vessel adjustable to the different heights represented by said annular shoulders, a plurality of latch members distributed around the margin of said plate and movable radially into and out of engagement with the shoulder with respect to which the plate is adjusted and at any point in the circumference of said shoulders, an operating handle carried by said plate for actuating said latch members, a compressor plate within the vessel spaced from said plate, and means for forcing said compressor plate toward said plate to squeeze water from clothes positioned between said plate and said compressor plate.
7. In a structure of the class described, the combination of a cylindrical vessel having a closed bottom and an open upper end and having integrally formed in its side wall a plurality of annular corrugations arranged in parallel spaced relation, a removable cover plate relatively adjustable in said vessel to different levels represented by said corrugations, segmental latching members disposed around the margin of said cover plate and radially movable into and out of engagement with said corrugations at any points in the circumference thereof, a rotary operating handle on said cover plate for actuating the latching members, and means associated with said vessel for compressing the clothes against said cover plate to squeeze the water from the clothes.
8. In a clothes drier of the class described, the combination of a cylindrical receptacle for the clothes, open at its upper end and having a plurality of parallel annular grooves formed in its wall, a removable cover member forming a stationary head adjustable to different depths within said receptacle corresponding to said grooves and means for positioning said cover member at said different depths and including radially movable locking members carried by said cover member adapted to engage said grooves at any point in the circumference thereof, a compressor member spaced below said cover member within which space the clothes to be treated are positioned, and power mechanism for actuating said compressor member toward said cover member to squeeze the water from the clothes.

JOSEPH SEKAVEC.
